UNITED STATES PATENT OFFICE.

JAMES WARD PACKARD, OF WARREN, OHIO.

DESIGN FOR A FUSE-BLOCK BOX.

SPECIFICATION forming part of Design No. 24,465, dated July 9, 1895.

Application filed April 30, 1895. Serial No. 547,702. Term of patent 7 years.

To all whom it may concern:

Be it known that I, JAMES WARD PACKARD, of Warren, in the county of Trumbull and State of Ohio, have invented and produced a certain new and original Design for Boxes for Fuse-Blocks; and I do hereby declare the following to be a full, clear, and exact description of the invention, such as will enable others skilled in the art to which it appertains to make and use the same.

This is a design for boxes for electric fuse-blocks.

In the accompanying drawings, Figure 1 is a view in perspective. Fig. 2 is a cross-sectional view on the line $x-x$, Fig. 1. Fig. 3 is a central longitudinal sectional view.

The leading or characteristic feature of my design is the rectangular block A, having end

chamber a^3 extending inwardly from the top and a cylindrical passage a within the central portion a^2 . One of the chambers a^3 is made larger than the other. In one end wall of the block is an opening a' having opposite extensions a^4 , while in the other end wall is an opening b' . An opening b is formed in one side of the block.

I claim—

The design for a fuse-block box, substantially as herein shown and described.

In testimony whereof I have signed this specification in the presence of two subscribing witnesses.

JAMES WARD PACKARD.
